UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

RETAINER FOR PERCUSSIVE TOOLS.

Application filed October 2, 1922. Serial No. 591,735.

To all whom it may concern:

Be it known that I, FRANCIS A. JIMERSON, a citizen of the United States, and a resident of Athens, county of Bradford, 5 and State of Pennsylvania, have invented a certain Retainer for Percussive Tools, of which the following is a specification, accompanied by drawings.

This invention relates to tool retainers 10 for percussive tools but more particularly to a retainer of the type in which a sleeve or casing is adapted to be suitably held or secured on the end of the percussive tool in position to be engaged by the implement 15 sought to be retained within the percussive tool.

In percussive tools used as coal picks, tie tampers, and the like, the working implement or steel is subjected to severe impact 20 and various devices have been employed to cushion or yieldingly hold the retainer. In some of such devices the retainer is screw-threaded to the cylinder of the machine, many of the devices including springs or 25 other resilient metallic means as the sole or principal cushioning element, and breakage of the retainer or parts connected therewith is apt to occur.

One object of the present invention is to 30 simplify and improve the retainer construction and reduce the liability of breakage by more resiliently and effectively mounting or holding the retainer so that the movement of the retainer under the impact of the working implement or steel is effectively 35 cushioned.

Another object of the present invention is to employ fluid pressure as the principal cushioning agent for resiliently holding the 40 retainer against the impact of the percussive or working implement.

With the above and other objects in view I have devised the retainer construction described in the following specification and 45 shown in the accompanying drawings, forming a part hereof, in which—

Figure 1 is a side elevation partly in longitudinal section of a percussive tool of the type known as a "coal pick" with my improved retainer applied thereto;

Figure 2 is a transverse sectional view taken on the line 2—2 of Figure 1 looking in the direction of the arrows;

Figure 3 is a plan view of the retainer 50 locking spring;

Figure 4 is a perspective view partly in section, of one of the retainer locking rings, and Figure 5 is a side view of the front end of the machine showing the retainer as it appears in use.

Referring to the drawings, the invention has been shown in connection with a percussive tool of the type known as a "coal pick", in which the tool cylinder A is provided with a bore B and a piston C is 65 adapted to reciprocate in the bore B to actuate the percussive or working implement D, which may be a coal pick, tie tamper, core breaker, drill, or similar device.

The shank E of the implement D is 70 removably supported within a hollow sleeve or bushing F which is preferably pressed into or otherwise firmly secured within the bore G at the forward end H of the cylinder A, the sleeve F having a flange J which abuts against the cylinder end H and extends slightly beyond the outer edges of the cylinder end H. The shank E of the 75 steel may be either round or hexagonal, as shown, and the collar K is adapted to engage the flange J to limit the extent to which the shank E extends within the forward end of the cylinder end H.

The retainer proper comprises a cylindrical sleeve L which is adapted to surround the forward end H of the cylinder A, and as shown herein is provided with an aperture O through which the working end P of the implement D may be passed, so 85 that when the retainer is operatively secured on the percussive tool the flange J acts as a stop for properly positioning the retainer and also acts as a spacer between the outer wall of the cylinder end H and the inner wall of the retainer sleeve L, thus leaving a space Q at the forward end of the machine between the forward ends of the sleeve J and retainer sleeve L affording a limited amount of movement for the 90 percussive or working implement D. The flange J also serves as a stop for limiting the inward movement of the sleeve L. An annular chamber R is also formed between the forward end H of the cylinder A and 95 retainer sleeve L.

A resilient device, which may be a coiled spring S, located in the chamber R, serves to hold the retainer L against the flange or stop J. The spring S is compressed between 100 105 110

annular filling rings T at the opposite ends of the chamber R and an annular locking ring U is inserted in the open rearward end of the chamber R, this locking ring U preferably having a beveled surface V which is adapted to lie opposite a recess W in the inner wall of the retainer sleeve L so that a substantially circular split locking spring X may be inserted in the recess W and thus 10 engage the beveled surface V so that the ring U will be held within the chamber R under the pressure of the spring S. The end of the retainer sleeve L is cut away, as shown at Y, so that the straight ends or fingers Z 15 of the spring X may be manipulated and pressed together to remove the spring from or insert it within the recess W, during the assembling or disassembling of the retainer.

A fluid conveying passage a leads from 20 any desired source within the percussive tool to the interior of the chamber R, and during the operation of the percussive tool this chamber is constantly under fluid pressure, which may be the same fluid admitted at the 25 inlet d which operates the percussive tool, and which exerts pressure to cushion the retainer L against the impact of the blow administered by the collar K of the working implement D in its striking movement under 30 the influence of the blows of the reciprocating piston C. Packing rings b which are U-shaped in cross section between the filling ring T and flange J at one end of the chamber R and the filling ring T and locking ring U at the opposite end of the chamber R, serve to prevent the escape of fluid pressure from the chamber R.

The spring S does not appreciably cushion the retainer L, the motive fluid pressure 40 within the chamber R being depended upon as the principal cushioning agent. In the use of the present construction it is a practical impossibility for the cushioning means to be completely collapsed, as when springs 45 are employed, so that the retainer cannot strike forcibly against a rigid part of the tool or be itself rigidly held so that it could receive an uncushioned blow. Such disadvantageous conditions have resulted in 50 breakage of retainers in the past, but are obviated in the present construction.

I claim:

1. In a percussive tool having a cylinder and a collared working implement adapted 55 to extend into said cylinder, the combination of a bushing secured in the bore of the cylinder, a flange on said bushing forming a stop for limiting the inward movement of said implement in said cylinder, a cylindrical sleeve loosely surrounding the front end 60 of said cylinder and provided with a hole through which said implement extends, said collar on the working implement having limited movement between said sleeve and said 65 flange, pneumatic means for cushioning the

movement of said sleeve in one direction, spring means for holding said sleeve against said flange, an annular locking ring for closing one end of said sleeve, and means for locking said ring in place adapted to be 70 readily removed to permit disassembly of parts.

2. In a percussive tool having a cylinder and a collared working implement adapted to extend into said cylinder, the combination 75 of a bushing secured in the bore of the cylinder, a flange on said bushing forming a stop for limiting the inward movement of said implement in said cylinder, a cylindrical sleeve loosely surrounding the front end of 80 said cylinder and provided with a hole through which said implement extends, said collar on the working implement having limited movement between said sleeve and said flange, pneumatic means for cushioning the 85 movement of said sleeve in one direction, including a pair of annular rings between said cylinder and sleeve, means for introducing pressure fluid between the cylinder and sleeve, and packing carried by said rings for 90 preventing the escape of pressure fluid from the space between said cylinder and sleeve, a spring for holding said sleeve against said flange and seating at each end on one of said 95 annular rings, and means for closing one end of said sleeve.

3. In a percussive tool having a cylinder and a collared working implement adapted to extend into said cylinder, the combination 100 of a bushing secured in the bore of the cylinder, a flange on said bushing forming a stop for limiting the inward movement of said implement in said cylinder, a cylindrical sleeve loosely surrounding the front end of 105 said cylinder and provided with a hole through which said implement extends, the inward movement of said sleeve being limited by said flange, and said collar on the working implement having limited movement between said sleeve and said flange, 110 pneumatic means for cushioning the movement of said sleeve in one direction, including a pair of annular rings between said cylinder and sleeve, means for introducing pressure fluid between the cylinder and sleeve, and packing carried by said rings for 115 preventing the escape of pressure fluid from the space between said cylinder and sleeve, a spring for holding said sleeve against said flange and seating at each end on one of said 120 annular rings, and an annular locking ring for closing one end of said sleeve, a spring for locking said ring in place, and fingers on said spring for enabling said 125 spring to be readily removed to permit disassembly of the parts.

In testimony whereof I have signed this specification.

FRANCIS A. JIMERSON.
